CLAIM

The ornamental design for a smartphone with graphical user interface for a text selection box, as shown and described.

DESCRIPTION

FIG. 1 is a front view of a smartphone with graphical user interface for a text selection box showing our novel design; FIG. 2 is a front view of the smartphone with graphical user interface for a text selection box shown in an alternate configuration with the text selection box shown expanded when dragged;

FIG. 3 is a front view thereof, showing unclaimed text within the text selection box; and,

FIG. 4 is a front view of the smartphone with graphical user interface for a text selection box shown with a human hand in broken lines demonstrating direction to pull text selection box.

The broken lines are included for illustrative purposes only and form no part of the claim.
